United States Patent Office

Des. 203,950
Patented Mar. 1, 1966

203,950

BOTTLE

Clark E. Swayze, Midland, Mich., assignor to The Dow Chemical Company, Midland, Mich., a corporation of Delaware

Filed Apr. 15, 1965, Ser. No. 84,791

Term of patent 14 years

(Cl. D58—8)

FIGURE 1 is a side elevational view of a bottle showing my new design, the side opposite being a mirror image of the side shown;

FIGURE 2 is a rear elevational view thereof;

FIGURE 3 is a top plan view thereof;

FIGURE 4 is a bottom plan view thereof;

FIGURE 5 is a front elevational view thereof; and

FIGURE 6 is an enlarged perspective view thereof.

I claim:

The ornamental design for a bottle, as shown and described.
